COMBINED CALENDAR AND PAD HOLDER

Jacob S. Sherman, Chicago, Ill., assignor to Park Sherman Company, Chicago, Ill., a corporation of Illinois

Application March 1, 1955, Serial No. 34,807

Term of patent 14 years

(Cl. D74—1)

FIG. 1

FIG. 2

FIG. 3

FIG. 4

Fig. 1 is a top plan view of a combined calendar and pad holder showing my new design.

Fig. 2 is a side elevational view thereof.

Fig. 3 is a rear elevational view thereof.

Fig. 4 is a front elevational view thereof.

The dominant portions of the design are shown in full lines.

I claim:

The ornamental design for a combined calendar and pad holder, substantially as shown and described.
